UNITED STATES PATENT OFFICE

JULIUS C. SULLIVAN, OF PITTSBURGH, PENNSYLVANIA, ASSIGNOR TO GULF REFINING COMPANY, OF PITTSBURGH, PENNSYLVANIA, A CORPORATION OF TEXAS

TANK CAR CONSTRUCTION

Application filed April 6, 1931. Serial No. 528,160.

This invention relates to a tank car construction for maintaining the tanks of railway tank cars in stable equilibrium with the car body frame and for minimizing forces incident to tank car transportation which tend to destroy the tank. More specifically it involves tying the tank down tight on its bolsters by a plurality of stabilizing ties; all as more fully hereinafter set forth and as 10 claimed. Each tie comprises an adjustable tie bolt extending downward from a bracket on the side of the tank, through the car body frame to which the tank is to be tied, said tie bolt being provided with enlarged heads on each end and provided with a turnbuckle midway of its length to permit adjustment; the said bracket, permanently fastened on the outside of the tank shell, positioned approximately on the horizontal transverse axis of 20 the tank, and provided with a socket to receive and hold one enlarged head of the adjustable tie bolt; a helical spring mounted co-axially on the lower end of the tie bolt below that portion of the car body frame to which the tank is to be tied; a washer to 25 transfer the opposing forces between bolt head and spring.

One object of the present invention is to provide a means for constantly maintaining the tank of a tank car in tight contact with its cradles, the degree of tightness being greater than that resulting from the weight of the tank and contents.

Another object of my invention is to provide a means for resisting the tendency of the tank of a tank car to rise from its cradles when subjected to the forces arising during transit.

Another object of my invention is to maintain the tank as described in the two foregoing paragraphs, while permitting such sliding motion longitudinally as will provide for expansion and contraction with changes of temperature.

Another object of my invention is to prevent jumping of a tank in its cradles.

Another object of my invention is to prevent the tank from being thrown sidewise out of its cradles while the car is in motion on curved track.

Another object of my invention is to avoid the scraping of paint from the tank by anchor straps, and the consequent rusting.

Another object of my invention is to abolish anchor straps as an obstacle to inspection and tightening of rivets and seams.

Another object of my invention is to provide a positive tying of the tank to the car body frame, from a plurality of points approximately on the horizontal transverse axis of the tank.

Another object of my invention is to provide a tank tie which has its adjusting threads removed away from the end anchoring means. Where a bolt extends through end anchoring means with a fastening and adjusting nut beyond, it is common, where vibration and shock are present, to find that the fastening means has chewed the thread and precluded subsequent adjustment.

Tank cars commonly comprise trucks, a body frame, including bolsters, cradles, a tank, and straps for holding the tank in the cradles. The trucks are of the four wheel type commonly used in all railway rolling stock, and there is one truck at each end of the car. A body frame including body bolsters is mounted on the trucks and serves to maintain the trucks in their proper relation to one another, to carry the superstructure, to transfer the weight of the superstructure and its contents to the trucks, and it is fitted with coupling means at each end to permit the car to be connected with other cars into a train. Two or more cradles are mounted on the body frame and are adapted to receive the tank and hold it in position on the body frame. The tank is commonly a horizontal tank slightly shorter than the car frame and it has been the practice to tie the tank into the cradles and down to the car frame by means of a plurality of anchor straps.

This invention concerns stabilizing fasteners. These are intended to perform all of the functions of the common anchor straps, to perform additional functions, and to obviate all of the disadvantages of the common anchor strap. In addition to other features the stabilizing fasteners resist many forces which are generated in a tank car during transit.

and which are not adequately provided for by the common anchor strap.

When a tank car is at rest there is no need of either anchor straps or stabilizing fasteners, for the cradles will provide adequate support for the tank. But immediately upon coming into motion there arise strains which tend to disarrange the relation of tank and car and to destroy the tank. In considering each of these forces it is necessary to keep in mind that the combined weight of the tank and its contents when loaded is ordinarily much greater than the weight of the trucks and body frame of the car.

The anchor straps ordinarily used in tank car construction are flat bands which extend upward from the body frame on one side of the tank, wrap across the top of the tank in close contact therewith, and extend back down to the body frame on the opposite side. These straps are threaded on each end. They pass down through the deck of the body frame on each side and are fastened by a nut on the under side. It is impossible to keep these straps tight in tank car operation, and however tight they may be made when a car is constructed and when it is sent to a car shop, the severe and frequent shocks and vibrations incident to travel acting on these straps, which have no "give" or elasticity, loosens them within a few days' movement, and thenceforth they exert no effect in maintaining the tank in tight contact with the cradles. The looseness of these elements, even though moderate, considerably shortens the life of the tank car and adds greatly to its upkeep cost. Because it is not such a condition as threatens immediate destruction of the tank it is often subordinated to other considerations of operation. It is the purpose of this invention to replace anchor straps, which perform a very modest function, with elements which better perform the function of an anchor strap and which perform a number of additional and valuable functions, and which add very materially to the life of the tank.

The relative destructive effects of ordinary track jolting on a loosely secured tank and a tightly secured tank can easily be appreciated by considering the destructive effect of an air hammer working upward on some body which rose with each blow and each time fell back, with its resultant momentum, just in time to catch the full force of the next blow. It is common knowledge that such conditions would be much more destructive than if the same body were rigidly or almost rigidly attached to the striking end of the air hammer. In the air hammer analogy, with a tight connection of the hammer and the body being struck, a much greater portion of the generated force will be absorbed by the medium supporting the air hammer, and less of it transferred to the attached body. Just so

with the tank car. When the tank is maintained at all times in tight contact with the cradles, a much greater portion of the force generated will be absorbed in the car springs, and that which is transferred to the tank will be transferred less sharply and with proportionately less destructive effects. It will be noted that these considerations apply to all of the track jolts incident to railway transportation—those which occur in every track length of travel.

The principal forces which tend to destroy the tank of a tank car are (1) longitudinal forces resulting mainly from changes in the velocity of car travel, (2) vertical forces resulting from track inequalities and tending to cause bouncing of the tank in its bolsters, (3) transverse forces of relatively great magnitude tending to throw the tank sidewise out of its bolsters, (4) transverse forces of lesser magnitude but relatively high frequency, resulting from inequalities of opposite rails of the track, and (5) a tendency of the tank to rotate on its longitudinal axis, jamming the drawoff nozzle against the channels of the body frame, thereby loosening that nozzle and threatening loss of the entire contents. All of these forces are much amplified and complicated when the car is loaded below the dome and surging takes place.

This invention, by providing a means for maintaining the tank in tight contact with its bolsters under all conditions of travel, minimizes the attrition resulting from the destructive forces mentioned, adds greatly to the life of the tank, and very materially reduces cost of upkeep. This invention comprises means for maintaining it in necessary adjustment and the design brings the adjusting element into an accessible position, uses as the adjusting element one which can be adjusted with the aid of such tools as are commonly at hand in railroading practice, and isolates the means of adjustment away from end fastening means which tend to chew, chafe, and destroy the thread and preclude subsequent adjustment.

This application includes drawings illustrating the invention and provided with reference numerals to indicate the various parts.

Fig. 1 is a side view of one end of a tank car, principally in elevation, and partly in section.

Fig. 2 is an end view of a tank car, in elevation.

Fig. 3 is an enlarged fragmentary view, partly in section, showing the means and mode of fastening to the tank.

Fig. 4 is a view in perspective of one of brackets illustrated in Fig. 3.

Fig. 5 is a view in perspective of a washer used to transfer forces between the lower, enlarged, end of bolt 14 and spring 25.

Fig. 6 is a sectional view of the washer il-

lustrated in Fig. 5, the section being on a plane coincident with the vertical axis.

In the drawings 1 represents one of the car trucks, 2 the body frame which comprises 5 horizontal channels 3 and the transverse bolsters 10. A car coupling means 4 is provided. Cradles 12 are mounted on the car frame and are here shown mounted on the bolsters 10. The tank 11 is carried in the bolsters 10. 10 These parts are of common form and relation and constitute no part of the present invention.

The invention is a stabilizing tie arranged to tie the tank to the car body frame and 15 maintain it tight in its cradles. Each stabilizing tie comprises an adjustable tie bolt and its terminal fastening and tensioning means. The tie bolt consists of two links 13 and 14, together with their connecting turnbuckle element 15. The element 15 and the 20 ends of links 13 and 14 which fit thereinto are threaded to permit adjustment of their length when assembled. The links 13 and 14 are preferably solid bars and at their remote 25 ends they are upset to provide an enlarged head as shown at 22 in Fig. 3.

Attachment means for the bolt is provided on the tank 11 by a bracket shown in Fig. 4. The bracket is fastened to the tank shell by 30 rivets 18 and is preferably positioned approximately on a horizontal transverse axis of the tank. The base 16 of the bracket is curved to conform to the curvature of the tank shell, and provided with openings 17 35 to receive attaching rivets 18. Extending outward from the base 16, and parallel to one another, are two flanges or ribs 19, preferably of the outline shown, which flanges are reinforced by webs 20. The extremities of the 40 two spaced flanges 19 are connected in their upper portion by a wall 21 and these three elements, together with the base 16, form a vertical enclosure of square cross section, open at the top. This enclosure is of a size 45 adapted to receive the enlarged head 22 of a bolt 13, and the lower part of this enclosure is reduced by a shoulder 23, leaving therebelow a circular opening 24 only slightly larger in diameter than the body of bolt 13. When 50 the stabilizing tie is fully assembled, the enlarged head 22 of bolt 13 rests on shoulder 23 and the opposing forces of the tank and tie are transferred at this point.

The lower section 14 of each tie passes 55 through an opening provided in the body bolsters 10 or other portion of the car body frame. A helical spring 25 is mounted coaxially on the lower end of bolt 14, below that portion of the car body frame to which 60 attachment is to be made and above the previously described enlarged head at the extremity of 14. This spring is held in place and the opposing forces of the spring and bolt are transmitted to one another by a washer 65 26 mounted on bolt 14 and retained against

its enlarged terminal head. This washer is provided with a central opening 27 for the bolt shank and with a recess 29 to receive and position the spring. Flange 28 and webs 30 serve to strengthen the washer and flange 28 70 is of such form as to resist relative rotation if the head of the bolt 14 is square, which it advantageously may be. While the washer is here illustrated in simple form it may if desired also have provision to prevent its rotation during adjustment of the tie.

While my invention has been illustrated and described particularly with reference to its applicability to railway tank cars it will of course be understood that it is equally applicable to tanks mounted on all form of conveyances including particularly automobile tank trucks. The terms vehicle and conveyance are used synonymously in this application.

While my invention has been described particularly with reference to cylindrical tanks it is equally applicable to tanks of elliptic cross section and is applicable in large extent to flat bottom tanks which rest directly 90 on the flat bottom of a vehicle.

The most advantageous embodiment of my invention has the tie attached to the tank at a point very close to a horizontal transverse axis of the tank and extending vertically 95 downward from this point of attachment to its lower point of attachment. However, attachment to the tank at the point described is not indispensable nor is it indispensable that the tie should reach downward in a 100 strictly vertical position. Ties should always be mounted geometrically opposite to one another and opposite ties should always be in the same plane. Variation from the vertical position does not seriously reduce the efficacy of the tie until the variation approaches thirty degrees from the vertical, unless, of course, the deviation from the vertical would seriously reduce the distance 105 between the ties at their lower ends. The brackets should in all cases be of such design that the bolts 13 and turnbuckles 15 will not touch the tank shell.

My invention contemplates the use of my ties in pairs, and where the tank does not rest on a continuous support from end to end of the vehicle it is most desirable to mount the ties in line with the cradles which carry the tank, tying it directly downward thereon.

The adjustability of length of my ties is 115 important only in so far as it is a means to adjust the tension of the tie and in so far as it permits me to limit the total "give" or extensibility of the tie when adjusted. The latter of these considerations is of practical 120 importance as it is desirable to have the spring in ordinary condition of compression so near to its length under total compression 125 that the total possible extension of the tie resulting from pull of the tank could never 130

be sufficiently great to permit axial rotation of the tank to a point where the bottom drawoff nozzle would touch the longitudinal beams 3 of the body frame.

5 While I have shown and described my invention as including the use of a washer 26 in each tie to transfer the opposing forces between the spring 25 and the bolt 14, this is altogether a matter of structural convenience and it is equally practical to make the head of bolt 14 of a size to directly engage the spring, thus doing away with the necessity for a washer.

15 Obviously the bracket shown in Fig. 4 may be attached to the tank by welding or any other suitable means.

What I claim is:

1. A stabilizing tie to prevent bouncing of conveyed tanks on their conveyance during 20 travel, the tie comprising a bracket, two bolts each carrying an enlarged head on one end and a threaded portion on the other end, a turnbuckle, a washer, and a helical spring; said bracket being permanently fastened to the outside of the tank shell and adapted to receive and retain the enlarged end of one of said bolts; the other of said bolts carrying the washer on its shank and retaining it by means of its enlarged head, carrying the helical spring on its shank and retaining that by means of the washer, its threaded end extending upwardly through a hole in the body of the conveyance and holding the helical spring thereagainst, and connected at its threaded end by the said turnbuckle to the threaded end of the other bolt depending from the said bracket.

2. A stabilizing tie to prevent bouncing of conveyed tanks on their conveyance during 40 travel, the tie comprising a bracket, two bolts each carrying an enlarged head on one end and a threaded portion on the other end, a turnbuckle, and a helical spring; said bracket being permanently fastened to the outside of the tank shell and adapted to receive and retain the enlarged end of one of said bolts; the other of said bolts carrying the helical spring on its shank and retaining it by means of its enlarged head, its threaded 45 end extending upward through a hole in the body of the conveyance and holding the helical spring thereagainst, and connected at its threaded end by the said turnbuckle to the threaded end of the other bolt depending from the said bracket.

3. The combination with a vehicle and a horizontal tank mounted thereon, of means to maintain stability of the tank with relation to the car, said means comprising tie elements of adjustable length and tension, used in pairs, the two elements of a pair having their upper terminals attached to opposite sides of the tank, having their lower terminals attached to the car below the point of attachment to the tank, and each being

fitted with a spring at one terminal to maintain the tie continuously in tension.

4. The combination with a railway tank car of means to uninterruptedly maintain the tank in tight contact with the car during 70 travel, said means comprising ties extending vertically downward to opposite ends of each car bolster from opposite sides of the tank shell, said ties being adjustably maintained under tension by means of a spring, and said ties comprising two bolts adjustably connected by means for altering length and tension.

5. The combination with a railway tank car of means to uninterruptedly maintain the tank in tight contact with the car during 80 travel, said means comprising ties extending vertically downward to opposite ends of each car bolster from opposite sides of the tank shell at points on a horizontal transverse axis of the tank, said ties being adjustably maintained under tension by means of a spring.

6. The combination with a railway tank car of means to uninterruptedly maintain the tank in tight contact with the car during 90 travel, said means comprising ties extending vertically downward to opposite ends of each car bolster from opposite sides of the tank shell, said ties being adjustably maintained under tension by means of a helical spring under compression, and said ties comprising 95 two bolts adjustably connected by means for altering length and tension.

7. The combination with a railway tank car of means to uninterruptedly maintain the tank in tight contact with the car during 100 travel, said means comprising ties extending vertically downward to opposite ends of each car bolster from opposite sides of the tank shell, said ties being maintained under tension by means of a helical spring under compression and the tension being adjustable by means of a turnbuckle positioned above the car bolster.

8. The combination with a vehicle and a tank mounted thereupon of means to uninterruptedly maintain the tank in tight contact with the vehicle during travel, said means comprising ties extending vertically downward from points directly opposite one another on the tank shell, through the supporting body frame, and maintained in tension by means of a helical spring under compression between the end of the tie and the under side of the vehicle bodyframe, and said ties comprising two bolts adjustably connected by means for altering length and tension.

9. The combination with a vehicle and a tank mounted thereupon of means to uninterruptedly maintain the tank in tight contact with the vehicle during travel, said means comprising ties extending vertically downward from points directly opposite one another on the tank shell, through the supporting body frame maintained in tension 120

by means of a helical spring under compression between the end of the tie and the under side of the vehicle body frame and the tie tension being adjustable by means of a turnbuckle positioned above the body frame where the spring is supported.

- 5 10. The combination with a vehicle and a tank mounted thereupon of means to uninterruptedly maintain the tank in tight contact with the vehicle during travel, said means comprising ties extending downward from points directly opposite one another on the tank shell, through the supporting body frame, and maintained in tension by means 15 of a helical spring under compression between the end of the tie and the under side of the vehicle body frame, and said ties comprising two bolts adjustably connected by means for altering length and tension.
- 10 20. 11. The combination with a vehicle and a tank mounted thereupon of means to uninterruptedly maintain the tank in tight contact with the vehicle during travel, said means comprising ties extending downward from 25 points directly opposite one another on the tank shell, through the supporting body frame maintained in tension by means of a helical spring under compression between the end of the tie and the under side of the vehicle body frame and the tie tension being 30 adjustable by means of a turnbuckle positioned above the body frame where the spring is supported.

In testimony whereof, I have hereunto affixed my signature.
